(57) **CLAIM**

I claim the ornamental design for a sleeper's combined blindfold and ear muffler, as shown and described.

DESCRIPTION

FIG. 1 is a perspective view of a sleeper's combined blindfold and ear muffler showing my new design;

FIG. 2 is a front elevational and outstretched view thereof; FIG. 3 is a rear elevational and outstretched view thereof; FIG. 4 is an end elevational and outstretched view thereof, the elevational view of the opposing end being a mirror image thereof; and,

FIG. 5 is a top plan and outstretched view thereof, the bottom plan view being identical thereto.

1 Claim, 3 Drawing Sheets

FIG. 2.

FIG. 5.

FIG. 3.

FIG. 4.
